UNITED STATES PATENT OFFICE.

SIDNEY A. KELLER, OF NEW YORK, N. Y., ASSIGNOR TO R. BLACKINTON & COMPANY, OF NORTH ATTLEBORO, MASSACHUSETTS, A FIRM.

DESIGN FOR A HANDLE FOR SPOONS, FORKS, OR SIMILAR ARTICLES.

SPECIFICATION forming part of Design No. 35,965, dated June 24, 1902.

Application filed May 31, 1902. Serial No. 109,802. Term of patent 7 years.

To all whom it may concern:

Be it known that I, SIDNEY A. KELLER, a citizen of the United States, residing at New York, in the county of New York and State of New York, have invented and produced a new and original Design for the Handle of a Spoon, Fork, or Similar Article, of which the following is a specification, reference being had to the accompanying drawings, forming part thereof.

Figure 1 is a view of the front or obverse side of the handle, showing my design. Fig. 2 is a view of the rear or reverse side of the same. The bowl of a spoon is shown in solid lines in both figures, and the tined blade of a fork is indicated in broken lines.

As shown in the drawings, the leading or material feature of my design consists of the representation in relief of intertwined grasses having twisted or scrolled pointed ends. On the obverse side of the handle the stem is ornamented with crossed grasses having twisted ends. Bulbs are interspersed with

the grasses. A floral ornament at the junction of the stem with the blade of the handle forms the base, from which a series of crossed and twisted blades of grasses extend to the upper end of the handle and support floral ornaments. On the reverse side oppositely-disposed blades of grasses with inter-twisted pointed ends form the margins of the handle and inclose a plain central panel.

Having described my invention, what I claim as new, and desire to secure by Letters Patent, is—

The design for the handle of a spoon, fork or similar article, as herein shown and described.

In testimony whereof I have signed my name to this specification in the presence of two subscribing witnesses.

SIDNEY A. KELLER.
